UNITED STATES PATENT OFFICE.

LEONIDAS G. WOOLLEY, OF INDIANAPOLIS, INDIANA, ASSIGNOR TO HENRY H. McGAFFEY AND CHESTER BRADFORD, BOTH OF SAME PLACE.

CUT-OUT FOR ELECTRIC LAMPS.

SPECIFICATION forming part of Letters Patent No. 350,519, dated October 12, 1886.

Application filed November 16, 1885. Serial No. 182,906. (No model.)

To all whom it may concern:

Be it known that I, LEONIDAS G. WOOLLEY, of the city of Indianapolis, county of Marion, and State of Indiana, have invented certain 5 new and useful Improvements in Cut-Outs for Electric Lamps, of which the following is a specification.

The object of my said invention is to produce a cut-out for electric lamps whereby, 10 when the lamp is broken, a short or cut-out circuit will be provided for the electric current.

This object is accomplished by providing a pivoted bridge-piece capable of being operated by a spring after being started, and a shunt-circuit containing an electro-magnet of high 15 resistance, the armature of which is connected to the pivot of the bridge-piece, whereby when, by the breaking of the lamp or lamp-circuit, the current is forced through said shunt-circuit, said electro-magnet will be energized and the armature operated to start said bridge-piece, when its movement will be completed by the spring, and it thus brought into contact with the two rods or wires running to the 20 lamp, bridging them, and forming the short or cut-out circuit.

Referring to the accompanying drawings, which are made a part hereof, and on which similar letters of reference indicate similar 25 parts, Figure 1 is a top or plan view of a lamp-support provided with my invention; Fig. 2, a side elevation of the same, the bridge-piece being shown in the position which it occupies when the lamp is cut out; Fig. 3, a horizontal sectional view looking downwardly from the dotted line 3 3 in Fig. 2; Fig. 4, a similar view with the armature in the position to which it is drawn by the electro-magnet when energized, and Fig. 5 a vertical sectional 30 view looking toward the right from the dotted line 5 5 in Fig. 1.

In said drawings, the portions marked A represent the base; B B', the rods or wires running to the lamp; C, the helices of the electro-magnet; D, a frame-work carrying said helices, their armature, and the bridge-piece; and E, said bridge-piece. The base A supports the rods B B', the frame-work D, and has usually binding-posts *a a'*, to which the line-wires are connected. The rods B and B' are secured to this base, and the upper ends are

secured to the points or wires connected with the illuminating portion of the lamp. An incandescent lamp is shown; but my invention may, by suitable changes in construction, be applied also to arc-lamps. Two helices, C, are shown, which are of high resistance and are set into a shunt-circuit. In the ordinary operation of the lamp, while the current is flowing through it, but little of the current passes 55 through this shunt-circuit, and consequently the helices exert but little power on the armature. When, however, the main or lamp circuit is broken, the current being forced through the shunt-circuit energizes said helices, and 60 they operate to draw their respective ends of the armature toward themselves, thus (said armature being arranged at somewhat of an angle with the central line passing through them) starting the bridge-piece (which is 65 mounted on the same pivot or shaft therewith) and permitting the cut-out to be operated. The frame D serves as a base for the helices of the electro-magnet and as a support for the pivot-shaft on which the armature and bridge-piece are mounted. The spring D', which is 70 employed in the invention, may also be secured thereto. The bridge-piece E is provided with a pivot-shaft, E', on which it and the armature C of the electro-magnet are mounted. 75 Said pivot-shaft is located centrally between the two helices of the magnet, thus enabling each of said helices to exercise an equal power upon the corresponding end of the armature. The point *e* of the bridge-piece is made somewhat wedge-shaped, as shown most plainly in 80 Fig. 3, in order that it may wedge in tightly between the rods B and B' and form a perfect electrical contact therewith. The shank of the bridge-piece extends out somewhat on the opposite side of the pivot from its head, as shown most plainly in Fig. 4, and to this extended portion is secured, by a pivot, *e'*, a connecting rod or link, E', which engages with and is operated by the spring D' on the frame D. 85

The operation is as follows: When the lamp is to be used, the parts are arranged as shown in Fig. 1, in which arrangement the bridge-piece occupies such a position that the force of the spring comes upon its pivot-shaft, and is 90 not in position to be effective to throw said bridge-piece around against the rods B and B'. 95

The armature of the electro-magnet (which is mounted upon the same pivot-shaft with said bridge-piece) is arranged, as shown, at an angle with the cores of the helices, so that when 5 said helices are energized they will pull said armature around a partial turn, (see Fig. 4,) sufficient to throw the bridge-piece into a position where the spring will act thereon. So long as the lamp is in working order, the comparatively small portion of the current which 10 passes through the shunt-circuit is not strong enough to effect this result; but should the lamp become broken or the connections therewith destroyed the increased current passing 15 through the shunt-circuit would cause the helices to pull upon and start the armature and parts connected therewith in motion, when, by the force of the spring D', the motion would be continued and the bridge-piece be driven between and into contact with the rods B and B', thus forming a short path for the electrical 20 current, (or cut out circuit,) as will be readily understood. The electro-magnet might, of course, be so arranged as to effect the result 25 without the aid of the spring in connection therewith, and I do not desire to confine myself to the use of such spring, preferring to regard it as a supplemental or re-enforcing device, which, while advantageous and valuable 30 as adding to the certainty of the operation, might be dispensed with without avoiding my invention.

Having thus fully described my said invention, what I claim as new, and desire to secure 35 by Letters Patent, is—

1. The combination, with an electric lamp, of an electro-magnet set in a shunt-circuit connected therewith, a pivot-shaft bearing the armature of said electro-magnet and a bridge-piece, and a spring connected with said bridge-piece, said several parts being arranged and operating substantially as set forth. 40
2. The combination of the rods or wires B B', helices C, frame D, carrying spring D', a pivot-shaft, E', mounted in bearings in said frame, carrying an armature and the bridge-piece, and a connecting-rod connecting said bridge-piece and said spring, substantially as set forth. 45
3. The combination of the main circuit of an electric lamp, a shunt-circuit, helices of 50 high resistance in said shunt-circuit, a pivot-shaft carrying the armature to said helices, and a bridge-piece, said armature being set in such relation to said helices that when said helices are energized by the current being 55 forced through them they will operatethrough said armature to turn said pivot-shaft and said bridge-piece, and bridge the rods or wires of the main circuit, thus cutting out or short-circuiting the lamp, substantially as set forth. 60

In witness whereof I have hereunto set my hand and seal, at Indianapolis, Indiana, this 10th day of November, A. D. 1885.

LEONIDAS G. WOOLLEY. [L. S.]

In presence of—

E. W. BRADFORD,
CHARLES L. THURBER.
